UNITED STATES PATENT OFFICE

ALLAN F. TURCK, OF SOUTH ORANGE, NEW JERSEY

MULTICOLOR PRINTING PRESS

Application filed August 6, 1931. Serial No. 555,451.

The invention relates to improvements in multicolor printing presses in which rotating printing couples are arranged in connection with cylindrical sheet-carriers to successively print in a single operation two or more colors in superposed relation to one another.

In this class of machines when operating upon sheets of relatively large size and of certain thin materials it has been found that the ordinary gripper advancing means is insufficient to prevent displacement and secure perfect register of the sheets, any drag thereon or irregular resistance during movement tending to warp and wrinkle the same.

The objects of the present invention include means consisting of a rotatably mounted cylindrical sheet-carrier provided with grippers and geared to pass in printing relation between the members of the several couples, the rotary engagement of the carrier surface over the entire bearing face of the sheets serving in part to relieve the strain upon the gripper actions and insuring the advancement of the sheets upon the carrier at a speed common with that of the printing speed without disturbing its adjustment with respect thereto.

For further comprehension of the invention, and of the objects and advantages thereof, reference is had to the following description and accompanying drawing, and to the appended claims in which the various features of the invention are more particularly set forth.

Referring to the drawing in which similar characters of reference designate like parts throughout the several views:

Figure 1 is a top plan view of a printing machine constructed in accordance with the present invention.

Figure 2, a transverse vertical section taken through the machine.

Figure 3, an enlarged transverse sectional view taken in side elevation of fragmental portions of a printing couple and showing the relation of the sheet-gripping connections.

Figure 4 is a rear end elevational view showing parts of a printing couple in con-

nection with the sheet-carrier, the impression cylinder and the sheet-carrier being partially shown in section.

Numerals 5 and 6 of the drawing show respectively the front and rear frames of the press transversely connected together by cross-braces 7, and upon the lower pair of the latter is fixed a work-platform 8. Projecting lengthwise from the opposite frames, upper and lower brackets are provided respectively indicated by 9 and 10, and slidably mounted upon said brackets are bearing frames 9a and 10a adapted to rotatably support the several plate cylinders 11, which latter operatively engage the opposite impression cylinders 12, rotatable in the opposite side frames 5 and 6, and jointly rotated for printing movement by their respective outer gears 13, shown by dotted lines in Fig. 2 and by full lines in Fig. 1.

For driving the main press and the latter gears a stub-shaft 14 is provided at its inner end with a bearing mounted in the rear frame 6 and at its outer end with a bearing 15, and between the bearings a driving pulley 16 is fixed to the shaft and adapted to be rotated from a source of power in any approved manner. Also upon the shaft 14 a relatively small gear 17 is fixed that engages on its opposite sides with the intermediate gears 18 leading to the gears 13 of the lower printing couples which latter gears in turn engage a second set of intermediates 19 which intermesh with the gears 13 of the upper printing couples.

The several printing couples are jointly arranged to present a circular printing path around which they are equally spaced apart, the circular path extending at its lower portion to include a sheet-feeding cylinder 38, and a delivery cylinder 39 for the printed sheets. Centrally disposed within the circular printing path of the couples is a sheet-carrier, generally indicated by 20, and comprising a pair of gear-rings 21 laterally spaced apart and fixedly secured together by five cross-braces 23 equally spaced around the rings in accordance with the corresponding spacing of the printing couples. Within the cross-braces are mounted a series of

sheet-grippers 24 adjustably secured by screws upon the gripper-shafts 25 rotatably supported in the opposite gear-rings and operable in the usual manner as indicated by 5 the lever 26, shown in Fig. 4. Fixed upon the cross-braces and rotatable therewith is a flexible sheet-carrying plate 27 having its outer surface alined in the circular printing path of the couples, and composed of suitable 10 material, as spring metal or other fibrous substances, and adapted to effect a driving engagement over the entire inner surface of the sheets to be printed. For further increasing the driving effect upon the latter, 15 exterior supply pipes 28 are arranged adjacent thereto and adapted to discharge heated air or other fluid pressure against the exterior printed surface of the sheets that serves both to press the same against the carrier 20 plate and effect a drying action upon the printed matter.

For the rotative support of the sheet-carrier a series of disk rollers 29 are journaled upon studs 30, fixed in the opposite frames 25 5 and 6 of the press, the rollers being arranged to engage the inner edge surfaces of the gear-rings 21 and laterally guide the same by side flanges projecting from the rollers. And for rotating the carrier the gear-rings 30 are provided with external gear teeth engaged by gears 22 fixed upon the opposite shaft-ends of the several plate cylinders 11, thus distributing the driving movement at several points around the gear-ring. In the 35 rotation of the carrier, the several gripper-bars 23 thereof, engage in clear relation the usual recesses 31 formed in the impression cylinders 12, as shown in Fig. 3, in which the ends of the blanket covering and make-ready 40 portions of these cylinders are indicated at 32 as provided with the ordinary and take-up connections 33 and 34, mounted in conventional manner. Also as indicated in the latter figure, the inner surface of the cylindrical 45 and flexible sheet-carrying plate 27 engages the resilient coverings of the several impression cylinders successively, perforations 35 being formed in the plate to receive the operating ends of the grippers 24 that engage 50 and hold the leading edges of the sheets 36 upon said plate to receive the impressions from the printing plates 37 shown in dotted lines upon the plate cylinders 11, the outer surface of the sheet-carrying plate being 55 alined in the printing path of said couples.

In the operation of the press, sheets may be fed in well-known manner to the grippers of the transfer cylinder 38 which are timed to co-operate with the carrier-bar grippers 60 24, the latter retaining the sheets throughout their continuous passage between the members of the several printing couples, whereby superimposed impressions in different colors may be made thereon, and the printed 65 sheets removed from the press by the deliv-

ery cylinder 39, and from which point the delivery may continue and the sheets distributed in any approved manner.

For severally adjusting the impressions made by the printing couples, the outer plate cylinders 11 are adapted to be separately tripped or outwardly displaced by the pivotally mounted levers 40 engaging the slidable bearing frames 9a and 10a, operable in any approved manner, the roller inking devices 41 applied to the several plate cylinders being also preferably mounted for joint movement therewith as affording desirable means of working up the ink distribution upon the printing plates prior to their regular print- 70 75 80

I claim:

1. In a printing press, a plurality of printing couples disposed to present a circular printing path, and a rotatably mounted cylindrical sheet-carrier movable between the members of said couples and having its outer surface alined in said printing path. 85

2. In a printing press, a plurality of printing couples disposed to present a circular printing path, a rotatably mounted cylindrical sheet-carrier movable between the members of said couples and having its outer surface alined in said printing path, means for feeding sheets to said carrier, and means for 90 95 delivering the printed sheets. 95

3. In a printing press, a plurality of printing couples disposed to present a circular printing path, a rotatably mounted cylindrical sheet-carrier movable between the members of said couples and having its outer surface alined in said printing path, inking devices for said printing couples, and means for detachably engaging the respective members of said printing couples. 100 105

4. In a printing press, a plurality of printing couples disposed to present a circular printing path, a rotatably mounted cylindrical sheet-carrier movable between the members of said couples and having its outer surface alined in said printing path, means for feeding sheets thereto, and means for applying a fluid substance to the printed surfaces of said sheets. 110

5. In a printing press, a plurality of printing couples disposed to present a circular printing path, and a flexible sheet-carrying plate cylindrically arranged and rotatable between the members of said printing couples and having its outer surface alined in 115 said printing path. 115

6. In a printing press, a printing couple having an outer plate cylinder, an inner impression cylinder provided with an outer flexible facing, and a flexible sheet-carrying plate cylindrically arranged and rotatable between the members of said printing couple, the outer surface of said sheet-carrying plate coacting with the printing face of said outer cylinder and the inner surface of said sheet- 120 125 130

carrying plate engaging the flexible facing of said impression cylinder.

7. In a printing press, a plurality of printing couples disposed to present a circular printing path, inking devices of different colors provided for said couples, and a rotatably mounted cylindrical sheet-carrier movable between the members of said couples and having its outer surface alined in said printing path.

13 8. In a printing press, a plurality of printing couples operatively connected together and disposed to present a circular printing path, a sheet-carrier comprising a pair of oppositely spaced gear-rings having external teeth and connected together by cross-braces, a cylindrical sheet-carrying plate fixed to said braces and alined in the printing path of said couples, means for rotatively supporting said gear-rings, and driving gears severally carried by said printing couples for engaging the teeth of said gear-rings.

9. In a printing press, a printing couple having an outer plate cylinder, an inner impression cylinder, a cylindrical sheet-carrier rotatable in a circular printing path extending between the members of said printing couple, and sheet-grippers operatively mounted on said carrier and adapted to engage the leading edge of a sheet.

25 10. In a printing press, a sheet-carrier comprising a pair of rings transversely spaced apart by brace members, grippers carried by said brace members, a cylindrical sheet-carrying plate mounted on said brace members, and sheet-grippers mounted on said brace members and operatively engaging said sheet-carrying plate.

40 11. In a printing press, a printing couple having co-operating plate and impression cylinders, and a rotatably mounted cylindrical sheet-carrier movable between said cylinders and having an outer surface disposed to fully support and advance a sheet for printing engagement.

45 12. In a printing press, a printing couple having co-operating plate and impression cylinders, a rotatably mounted cylindrical sheet-carrier movable between said cylinders and having an outer surface disposed to fully support and advance a sheet for printing engagement, and means for directing fluid pressure against the outer surface of the sheet.

50 13. In a multicolor printing press, a plurality of printing couples having each co-operating plate and impression cylinders, a rotatably mounted cylindrical sheet-carrier movable between the cylinders of said couples and having an outer surface disposed to fully support and advance a sheet for printing engagement by said couples.

Signed at New York in the county of New York and State of New York this 5th day of August A. D. 1931.
